UNITED STATES PATENT OFFICE.

CHARLES J. WOLF, OF MEMPHIS, TENNESSEE.

COIN-COUNTER.

SPECIFICATION forming part of Letters Patent No. 611,544, dated September 27, 1898.

Application filed November 23, 1897. Serial No. 659,587. (No model.)

To all whom it may concern:

Be it known that I, CHARLES J. WOLF, of Memphis, in the county of Shelby and State of Tennessee, have invented a new and Improved Coin-Counter, of which the following is a full, clear, and exact description.

This invention is an apparatus for receiving money and for automatically making change upon the striking by the operator of a key denoting the amount of the purchase.

This specification is the disclosure of one form of my invention, while the claims define the actual scope of the conception.

Reference is to be had to the accompanying drawings, forming a part of this specification, in which similar characters of reference indicate corresponding parts in all the figures.

Figure 1 is a front elevation of the invention. Fig. 2 is a sectional view on the line 2 2 of Fig. 3, showing the note-receptacles in elevation. Fig. 3 is a sectional view on the line 3 3 of Fig. 2. Fig. 4 is a horizontal section on the line 4 4 of Fig. 3. Fig. 5 is a fragmentary view illustrating one of the tumbler-plates by which the proper ejector-plates are thrown into operation when it is desired to secure a certain quantity of change. Fig. 6 is a detail section on the line 6 6 of Fig. 2. Fig. 7 is a detail section showing the means for controlling the five-cents ejector-plate. Fig. 8 is a detail section of the slide-plate at the upper end of the ten-cent-coin stack, by which slide-plate the devices of Fig. 7 are operated. Fig. 9 is a side elevation illustrating the five-dollar and ten-dollar note receptacles. Fig. 10 is a cross-sectional view of said note-receptacles. Fig. 11 is a fragmentary section of the note-receptacles. Fig. 12 is a fragmentary elevation of a part thereof. Fig. 13 is a detail section illustrating the ejector-plates and the coacting devices of the one-dollar-coin stack. Fig. 14 is a fragmentary plan view of the same parts. Fig. 15 is a detail section illustrating one of the locks for the ejector-plates. Fig. 16 is a fragmentary view, partly in section, showing the one-dollar-note receptacle and the arm that is operated by such receptacle for adjusting the ejector-plates. Fig. 17 is a view of the lock shown in Fig. 14 as well as of the dog for operating the same. Fig. 18 is a fragmentary view, partly in section,

showing the two-dollar-note receptacle and the means operated by said note-receptacle for adjusting the ejector-plates. Fig. 19 is 55 a detail view of the sectional shafting for adjusting the ejector-plates, and Fig. 20 is a section on the line 20 20 in Fig. 19.

The machine is mounted on a central base-plate 21 and on two side base-plates 22 and 60 23. The main or central base-plate 21 supports a casing 24, wherein is contained the mechanism for receiving and ejecting coin. The end plate 22 carries the five-dollar and ten-dollar note receptacles, and the end plate 65 23 carries the one-dollar and two-dollar note receptacles.

I will first describe the means for receiving the coin and for ejecting from the casing 24 the requisite change. Formed in the plates 70 of the casing 24 are five glass-faced coin-stacks 25, 26, 27, 28, and 29, respectively designed to receive dimes, nickels, quarters, halves, and dollars in coin. The coin are introduced into the coin-stacks through openings in the tops thereof. At the base of the coin-stack 25 two ejector-plates 30 are arranged. The plates 30 are mounted to slide horizontally on a bed-plate 31 and are superposed one upon the other, each ejector-plate 80 having an opening capable of receiving a dime, so that as the ejector-plates are moved outward one dime will be discharged for each plate. A shelf 32 is held rigidly at the front of the machine to receive the coin thus 85 ejected. At the base of the stack 26 two ejector-plates 33, similar to the plates 30, are arranged. At the base of the stack 27 one ejector-plate 34, similar to the previously-described ejector-plates, is arranged. At the 90 base of the stack 28 one ejector-plate 35 is arranged, and at the base of the stack 29 four ejector-plates 36 are arranged. These ejector-plates are shown collectively in Figs. 1 and 2.

95 Each ejector-plate is provided with a box 37. In coin-stacks where there are more than one ejector-plate the boxes 37 are offset laterally, so that the ejector-plates will be arranged in a pile one above the other and so 100 that the boxes will all slide on the bed-plate 31 in the same horizontal plane. This arrangement is illustrated best in Fig. 2. The coin-stack 26 for nickels is provided with two

ejector-plates, and consequently with two boxes 37. Fig. 7 shows one of the boxes 37 in detail. In this box is a vertically-movable locking-pin 38, that is normally entered in a vertical passage 39, formed in the bed-plate 31, whereby the particular box 37 and the attached slide 30 are locked to the bed-plate. A sliding pin 40 is held loosely in the passage 39, so as to be capable of engaging the pin 38 and pressing the same upward to release the ejector-plate 33 that is concerned with the pin 38. The pin 40 is raised by a lever 41, fulcrumed beneath the bed-plate, and actuated in turn by a rod 42, that is vertically slidable in the bed-plate and provided with a rounded head engaged by a cam 43 on the bottom of a sliding plate 44. The plate 44 is mounted in the top of the coin-stack 25, which is for dimes, and when a coin is pushed into the stack the plate 44 is moved rearward, the rod 42 is depressed, and the lever 41 is rocked to release the pin 38. There are two ejector-plates 33 for the coin-stack 26, but only one is controlled by the plate 44 of the coin-stack 25. The other ejector-plate 33 acts with mechanism to be hereinafter described. Now, when a dime is inserted into the stack 25 it may sometimes be desired to obtain one nickel for change. Consequently the above-described mechanism is provided, and this mechanism upon the insertion of the dime releases the said one of the ejector-plates 33 and permits one nickel to be obtained from the machine by certain key mechanism that will receive description hereinafter.

All of the boxes 37, with the exception of the one for the ejector-plates 33 and which has been just described, are normally unlocked from the bed-plate 31 in contradistinction to being normally locked to the bed-plate, as is the case with the box 37 having the pin 38 therein. Said boxes are provided with means by which they may be locked with the bed-plate to prevent the operation of the ejector-plates to which they are attached. The means consist, as shown in Figs. 13, 14, 15, and 17, of a spring-pressed pin 45, vertically movable in each box 37, (with the single exception of the box 37 having the pin 38.) Each pin 45 is capable of moving downward against the spring to engage a recess in the bed-plate 31. In order to hold the pins 45 in their lowered position, I provide a spring-pressed dog 46, that engages over the tops of collars arranged one on each pin 45. Consequently when the pins 45 are pushed downward the dogs 46 automatically engage with the said collars to hold the pins 45 downward and in locked position on the bed-plate. Mounted to slide transversely and arranged horizontally within the casing 24 is a carriage-bar 47, connected with a link 68, in turn connected to a lever 49. The lever 49 is operated by a horizontally-sliding push-bar 50, the front end of which projects through the front side of the casing 24. The carriage-bar 47 is provided with a series of holes respec-

tively adapted to receive the pins 45. The pins 45 are normally engaged with the carriage-bar 47, so that as the carriage-bar is drawn outward by the retractile springs 48 the boxes 37 which have their pins 45 engaged with the carriage-bar 47 will be moved outward with the carriage-bar, and the attached ejector-plates will be pushed outward, as shown with reference to one plate in Fig. 13, whereby a coin is discharged. Fig. 13 shows one of the ejector-plates 36 of the dollar-coin stack 29 pushed outward to deliver one dollar upon the shelf 32, which operation is accomplished by the connection of one of the boxes 37 of the series that are attached to the plates 36 with the carriage-bar 47.

The upper end of each coin-stack 26, 27, 28, and 29 is provided with a horizontally-movable slide-plate 51, similar to the slide-plate 44, excepting that no cams are attached to the plates 51. The slide-plates 44 and 51 respectively engage forwardly spring-pressed arms 52. A rigid shaft 57 carries four loose sleeves 53, 54, 55, and 56. The contiguous ends of each sleeve are mortised into each other, so that the sleeve 56 when rocked by the rearward movement of the attached arm 52 will not communicate movement to the sleeve 55, so that the sleeve 55 when moved rearward will communicate its movement to the sleeve 56, but not to the sleeve 55, so that the sleeve 54 when moved rearward will communicate its movement to the sleeve 53, and consequently to the sleeve 56, but not to the sleeve 53, and so that the sleeve 53 when moved rearward will not communicate its movement to the sleeve 54. The arms 52 that are devoted to the coin-stacks 25 and 26 are attached to the sleeve 53, the arm 52 of the coin-stack 27 is attached to the sleeve 54, the arm 52 of the coin-stack 28 is attached to the sleeve 55, and the arm 52 of the coin-stack 29 is attached to the sleeve 56. The sleeve 53 has three arms 58 rigidly attached thereto and projecting rearwardly therefrom. The sleeve 54 has a single arm 59, similar to the arms 58. The sleeve 55 has a single arm 60, similar to the arms before mentioned, and the sleeve 56 has four arms 61, also similar to the arms before mentioned. There are nine boxes 37, having each a pin 45, and there are nine arms 58, 59, 60, and 61, respectively coating with vertically-movable rods 62, held in a tubular frame-bar 63, which in turn is held rigidly by the casing 24 horizontally above the normal position of the carriage-bar 47. Each rod 62 is held up by a spring contained within the bar 63. The rearward movement of the arms 52 rocks their several sleeves and in turn transmits a downward movement to the appropriate arms 58, 59, 60, and 61, which in turn move downward certain of the rods 62. These rods 62, as shown best in Fig. 13, pass through the carriage-bar 47 and push the pins 45 downward out of engagement with the carriage-bar and into engagement with the bed-plate 31 of the three arms 58. Two of such

arms refer to the ejector-plates 30, while the third arm 58 acts with the second ejector-plate 53 or that plate which is not affected by the slide-plate 44.

5 Mounted at the forward portion of the machine are a series of spring-pressed keys 64. Each key 64 engages the leg 65 of a certain tumbler-plate. Each tumbler-plate consists in a leg 65, a horizontal body portion 66, and 10 a certain combination of upwardly-extending projections 67, standing on the body portion 66. The tumbler-plates are held to slide vertically in guides secured to the interior walls of the casing 24. Rocking on a transverse shaft 15 68^a are a series of levers 69. These levers 69 respectively engage the rods 62, so that upon the operation of the levers 69 the rods 62 will also be operated. The combinations of projections 67 on the tumbler-plates is such as 20 causes certain of the series of projections to engage certain of the levers 69. The keys 64 are provided with numbers ranging from "5" to "95" and representing cents, and from "1" to "5" and representing dollars. Each key moves 25 up a certain tumbler-plate, and the combination of projections 67 on that certain tumbler-plate moves downward such rod 62 as will lock with the bed-plate 31 all of the boxes 37 excepting those boxes which are attached 30 to the ejector-plates that will give from the machine change from the amount of money that was inserted in the machine. For example, assuming that fifty cents is tendered in payment of a thirty-cent purchase the 35 fifty-cent coin is inserted in the stack 28, which pushes rearward the corresponding plate 51 and throws the sleeve 55 rearward. This also turns the sleeve 56 rearward, which results in locking to the bed-plate the ejector-plates 40 for the coin-stacks 28 and 29. The ejector-plates of the other coin-stacks are left free to move. The change to be taken must be derived from the stacks 25, 26, and 27 and, with reference to the above-cited example, 45 never from the stacks 28 and 29. Now the operator presses down the key 64 having the number 30 thereon. This key lifts a certain tumbler-plate, which tumbler-plate has such a combination of projections 67 thereon that 50 the levers 69 which are related to the coin-stacks 26 and 27 are moved to throw down the corresponding pins 62 and lock the ejector-plates of the stacks 26 and 27. This leaves 55 unlocked the ejector-plates of the single coin-stack 25, which contains the dimes. There are two ejector-plates for the dime-coin stacks. Consequently when the rod 50 is pushed inward the carriage-bar 47 is moved forward, driving with it only the ejector- 60 plates of the stack 25, and consequently discharging two ten-cent pieces, which is twenty cents and which makes the change of fifty cents on a thirty-cent purchase. The machine is so constructed that normally upon 65 pushing inward the bar 50 coin will be ejected from every coin-stack excepting the coin-stack to which the pin 38 is related. When

a coin is inserted and when change is to be secured, the above-described mechanism operates to lock such of the ejector-plates as 70 are unnecessary and to leave unlocked those ejector-plates which will give out the proper coin in change. As the carriage-bar 47 moves outward it has no effect upon the dogs 46; but when the carriage-bar moves inward fingers 70, having a knuckle-joint connection with the bar, engage the several dogs 46 and disconnect the same from the pins 45. Consequently all of the pins 45 are moved upward out of engagement with the bed-plate 80 31 and again into engagement with the carriage-bar 47. The rod 50 is provided with a stud 71, that upon the inward movement of the rod operates an alarm-bell 72. A spring 73 presses the rod 50 inward. The rod 50 has 85 a projection 74 extending downward and normally engaging a spring-lifted lock-plate 75. The locking-plate 75 is in connection with the keys 64 by means of a downwardly-extending portion 67. (Shown in Figs. 1 and 2.) As the 90 keys 64 are moved downward the plate 75 is also moved downward, and the rod 50, by the action of the spring 73 and the springs on the arms 52, is drawn rearward, so as to operate the carriage-bar 47. This operation of the carriage-bar 47 is also assisted by the springs 48. 95

The above description being of the means for handling the coin does not extend to the means for handling the paper notes. I will now describe the mechanism for receiving the 100 notes and for giving the change therefrom.

The note-receptacles are designed for one-dollar, two-dollar, five-dollar, and ten-dollar notes. The one-dollar and two-dollar receptacles are arranged one above the other and 105 consist each in a stationary shell 77, which are held to end heads 78, attached to a standard 79, secured on the base-plate 23. A shaft 80 runs horizontally through each shell 77. These shafts 80 are shown with their outer 110 ends broken away in the drawings, but these outer ends in practice may be made to carry the work or other device by which the shafts may be turned. Each shaft also has a ratchet-wheel 81, pressed by a pawl 82, which prevents retrograde movement of the shafts. Fixed to the shafts 80 are the respective pocketed drums 83, which are exposed by openings 84 in the shells 77, and the detail construction of which will be described hereinafter 115 with reference to the five-dollar and ten-dollar receptacles. The inner ends of the pocketed drums 83 are respectively provided with heads 85 and 87, that turn with the note-receptacles and with the shafts 80. The heads 85 and 87 are provided with pins 86, projecting toward the casing 24. The pins 86 on the head 85 are designed to engage an arm 88, fixed on the sleeve 56, which is projected through one wall of the casing 24 to permit such an arrangement. Consequently as the head 85 is turned in the direction of the arrow shown in Fig. 16 120 the arm 88 will be rocked, as the dotted lines in said figure show, and the sleeve 56 will be 125 130

thrown rearward to lock the ejector-plates of the stack 29, for if one dollar is tendered to make a payment no change over one dollar will ever need be given. The pins 86 of the head 87 are designed to engage with an arm 89, fixed on a short shaft mounted in one side of the casing 24 and carrying within the casing 24 an arm 90, which in turn carries a bar 91, that engages under three of the levers 69 of the four levers 69 that are related to the stack 29, so that as a two-dollar bill is inserted within the two-dollar receptacle the arm 89 will be operated, which will throw upward the arm 90 and the bar 91 and cause three of the 15 ejector-plates in the stack 29 to be locked, leaving unlocked a single ejector-plate in the stack 29, which enables change of any amount lower than two dollars to be taken from the machine. When a note is inserted in either 20 of the one-dollar or two-dollar pocketed drums 83, such drums are turned one pocket by turning the shafts 80, which also turns the pins 86 and consequently causes the above-described 25 operation to take place with reference to the coin-ejector plates.

The five-dollar and ten-dollar note receptacles have no connection with the coin-stacks. These receptacles have such connection with each other so that upon placing a ten-dollar 30 note within its receptacle a five-dollar note may be withdrawn. The five-dollar and ten-dollar note receptacles have shafts 92, fixed in a standard 93 on the base-plate 22 and in the casing 24. Rigid exterior shells 94 35 close the shafts 92 and have heads 95, connected with the standard 93, so that the shells and heads are held rigid. Mounted to turn loosely on each shaft 92 is a sleeve 96. The sleeves 96 are provided with radial partitions 40, forming pockets in which the notes are placed. The note-receptacles for one dollars and two dollars are the same as those for five dollars and ten dollars. The shells 94 are provided with openings 98, through which the 45 notes may be passed. Each sleeve 96 is provided with a crank-arm 99, by which the sleeves may be turned, while the upper sleeve, or that in the ten-dollar-note receptacle, is provided with a ratchet-disk 100 and pawl 101 50 to prevent back movement of the parts. When a ten-dollar note is inserted within the appropriate receptacle, the crank 99 of the ten-dollar receptacle is turned to advance the sleeve 96 sufficiently to turn one partition 97 55 past the opening 98. This also turns the gear 102, which gear is fixed to the sleeve 96 of the ten-dollar-note receptacle. This transmits movement to the gear 103, which is loose on the shaft 96 of the five-dollar-note receptacle. 60 The gear 103 has an internal ratchet 104, engaged by a pawl 105, which is loosely carried on an arm 106, fixed to the shaft 96 of the five-dollar-note receptacle. Through the 65 means of this pawl 105 and arm 106 the turning of the gear 103 turns the partitions 97 of the five-dollar-note receptacle one point, so that as ten dollars is inserted and the note-

receptacle revolved to secure the ten-dollar a five-dollar note is uncovered and may be taken from the machine for change. When 70 a five-dollar note is inserted, the pawl 105 permits the partitions 97 of the five-dollar-note receptacle to be turned to secure the five-dollar note; but this turning of the five-dollar-note receptacle does not influence the ten-dollar-note receptacle. When five dollars and ten dollars are inserted in the machine, if it be necessary to take change smaller than the five dollars this may be done by operating the one-dollar and two-dollar note receptacles, which will also open for operation the coin-receptacles. 75 80

A series of levers 107 are mounted in the upper portion of the casing 24 and are provided with plates 108, on which numbers are 85 produced indicating the amount of the purchase. These levers 107 are operated by rods 109 in connection with the levers 69, and the arrangement is such that when a certain lever 69 is operated the proper amount will be 90 shown, by means of the plates 83, through an opening 110 formed in the front of the casing 24. The rods 109 are also in connection with a suitable recorder 111, that keeps a record of the transactions of the machine. 95

Having thus described my invention, I claim as new and desire to secure by Letters Patent—

1. The combination of a plurality of coin-stacks, an ejector-plate in each coin-stack, a carriage-bar, and means for connecting and disconnecting the ejector-plates with and from the carriage-bar, such means being actuated by the coin. 100

2. The combination of a coin-stack, a bed-plate, an ejector-plate sliding on the bed-plate and through the coin-stack, a box in connection with the ejector-plate, a lock-pin carried by the box, a carriage-bar movable over the bed-plate and capable of being engaged by the lock-pin to connect the ejector-plate with the carriage-bar, and means for actuating the lock-pin, such means being controlled by the coin. 105

3. The combination of a push-rod having a projection thereon, a lock-plate normally engaging the projection to hold the push-rod, and a key having connection with the lock-plate whereby to actuate the lock-plate upon the movement of the key. 110

4. The combination of an ejector-plate, a lock-pin for the ejector-plate, a dog spring-pressed to hold said lock-pin, a carriage-bar movable to operate the ejector-plate, and fingers carried by the carriage-bar and capable 115 of operating the dog. 120

5. The combination of two note-receptacles, a gear in fixed connection with one note-receptacle, a second gear loose on the remaining note-receptacle, an arm fixed to said note-receptacle, and a pawl carried by the arm and engaging the second gear. 125

6. The combination of a plurality of coin-stacks, ejectors working therein, a box in con-

nection with each ejector, a locking-pin working in each box, a bed-plate with which the locking-pins may be made to engage, a sliding carriage normally engaged by the locking-pins, a tubular frame-bar above the carriage, a series of rods mounted in the frame-bar and capable respectively of engaging the locking-pins to move them out of engagement with the carriage and into engagement with the bed-plate, and means for moving the rods and for moving the carriage.

7. The combination of a series of coin-stacks, a bed-plate below the same, ejectors sliding on the bed-plate and through the coin-stacks, a box carried by each ejector, locking-pins respectively carried in the boxes, a carriage located above the boxes and normally engaged by the locking-pins, the locking-pins being capable of engagement with the bed-plate when moved downward out of engagement with the carriage, means for pushing the locking-pins downward out of engagement with the carriage, and means for sliding the carriage.

25 8. The combination of a plurality of coin-stacks, a slide-plate in the top of each coin-stack, ejectors in the bottoms of the coin-stacks, a box carried by each ejector, a locking-pin working in each box, a bed-plate on which the ejectors are slideable and with which the locking-pins may engage to hold the bed-plate immovable, a carriage above the boxes and normally engaged by the locking-pins thereof so that the bed-plate may be moved 35 with the carriage, a tubular frame-bar above the carriage, rods carried in the frame-bar and respectively capable of downward movement to push the locking-pins from engagement with the carriage, a plurality of sleeves 40 mounted to turn and having mortised connection, and arms attached to the sleeves and respectively engaging the slide-plates and the rods.

9. The combination of a coin-stack, a bed-plate below the same, an ejector sliding on the bed-plate and working in the coin-stack, a carriage slideable over the ejector, means for locking the ejector with the carriage, a vertically-movable rod held above the carriage 50 and capable of releasing said locking means, a slide-plate in the top of the coin-stack, and means for transmitting movement from the slide-plate to the rod.

10. The combination of a coin-stack, a bed-plate at the bottom thereof, ejectors sliding on the bed-plate and through the coin-stack, a carriage movable over the ejectors, means for locking the ejectors with the bed-plate or with the carriage, vertically-movable rods 60 held above said locking means and capable of actuating the same, key-levers, tumblers actuated thereby, and additional levers for transmitting movement from the key-levers to the rods.

65 11. The combination with a casing, of a bed-plate mounted therein, a series of coin-stacks

mounted on the bed-plate, ejectors sliding on the bed-plate and into the coin-stacks, slide-plates mounted respectively in the upper portions of the coin-stacks, a carriage movable 70 over the bed-plate, means for locking the ejectors with the carriage or with the bed-plate, vertically-movable rods actuating said locking means, a series of rocking sleeves having mortised connection with each other, arms attached to said sleeves and respectively engaging the slide-plates and the vertically-movable rods, levers engaging the vertically-movable rods to impart movement thereto, a series of tumblers serving to impart movement to the levers, and key-levers serving to operate the tumblers.

12. The combination of a plurality of coin-stacks, a bed-plate mounted beneath the same, ejectors working in the coin-stacks and on the bed-plate, a carriage slideable over the bed-plate, means for locking one of the ejectors with the carriage or with the bed-plate, a slide-plate mounted in one of the coin-stacks and having a cam thereon, a vertically-reciprocal rod moved by the cam, a lever actuated by the rod, and a sliding pin held in the bed-plate and pushed by the lever, the pin serving to throw the locking means from engagement with the bed-plate and into engagement 90 with the carriage.

13. The combination of two coin-stacks, an ejector working in the first coin-stack, a bed-plate on which the ejector rests, a carriage, means for locking the ejector either with the bed-plate or with the carriage, such means being normally engaged with the bed-plate, a slide-plate working in the second coin-stack, and means actuated by the slide-plate for controlling the locking device of the 105 ejector.

14. The combination of a coin-stack, a bed-plate, a plurality of ejectors sliding on the bed-plate and movable through the coin-stack, a carriage, means for individually locking the ejectors either with the bed-plate or with the carriage, key-lever-actuated devices for controlling said locking means, and additional devices for controlling said locking means, such additional devices being set in motion by the insertion of a coin into the coin-stack.

15. The combination with a casing or rigid frame structure, of a coin-stack, ejectors working in the coin-stack, a carriage, means for locking the ejectors either with the carriage or with the frame structure, key-lever-actuated devices for controlling said locking means, and additional devices for controlling said locking means, such additional devices 125 being actuated by the insertion of a coin in the coin-chamber.

16. In a cash-register, a receptacle for notes of different denominations, the receptacle comprising two rigid exterior shells forming casings, a drum mounted in each shell and provided with boxes respectively for the notes,

and gearing connecting the drums to turn in unison.

17. In a cash-register, the combination with devices for handling the coin, of note-receptacles comprising two rigid exterior shells, a drum mounted to turn in each shell, the drums having boxes respectively for the notes, gear-

ing connecting the drums to turn in unison, and means for transmitting movement from the drums to the coin-handling devices.

CHARLES J. WOLF.
